KEY HOLDER

Ralph C. Root, Indianapolis, Ind.

Application April 18, 1934, Serial No. 721,097

8 Claims. (Cl. 150—40)

This invention relates to the art of key holders, particularly of the type adapted to hold keys in varying numbers. A primary object of the invention is to provide a simple holder which will effectively retain the keys and so enclose them that when one key is removed from the covering means, the remainder of the keys will not cause damage to the walls adjacent the key holder into which the used key is inserted. A further primary object of the invention is to provide a key holder ordinarily retaining the keys in a covered position and which may be operated merely by stretching so as to make any one of a number of keys therein available for use. A further primary object of the invention is to provide a means for mounting the keys within the holder so that the keys will be retained therein in varying number without having to abut screw members or the like to compensate for the difference in number of keys in the holder.

These and other objects will become apparent to those versed in the art in the following description of the invention as illustrated in one particular form by the accompanying drawing, in which

Fig. 1 is a side elevation of a holder embodying my invention;

Fig. 2, an end elevation;

Fig. 3, a top plan view;

Fig. 4, a section on the line 4—4 in Fig. 1, and

Fig. 5, a side elevation showing the holder in a distorted position permitting the release of a key.

Like characters of reference indicate like parts throughout the several views in the drawing.

I form an elastic body 10, preferably made out of a durable rubber to have an end pocket 11 from which side walls 12 and 13 extend. Near the outer ends of these side walls are positioned bosses 14 and 15, respectively, on their outer faces. Each of these bosses is provided with a central depression therein, and the walls are pierced by holes centrally through these depressions to receive the male and female portions of a bolt 16. The heads of the bolt 16 are of the proper diameter so as to just fit snugly into the depressions in the bosses 14 and 15 so that the inner annular wall of the boss will frictionally engage the periphery of the bolt head therein.

The pocket 11 as herein shown is preferably formed to have the walls 12 and 13 by extensions form the side walls thereof while the top end and bottom walls are formed of an integrally uniting narrow width of the rubber material, the end wall preferably curving around so as to

have the pocket rounded internally and externally. A rib 17 is preferably provided around the edges of the extending walls 12 and 13 and across between their junctures with the pocket end of the body.

On one side of the body 10 is provided a button 18 the purpose of which is to permit the user of the holder to determine that particular side of the holder in the dark or without glancing at the holder so that the key on that particular side of the holder may be located. This button further is employed to provide a means of gripping the body end of the holder firmly between the thumb and forefinger so that when the holder is to be stretched longitudinally, the body end will not readily slip out of the grasp.

In using the holder, the bolt 16 is removed by turning one of the ends from the outside and the desired number of keys, here shown as three in number in Figs. 3 and 4, are engaged by passing the bolt 16 back through the holes in each of the side walls 12 and 13 and having the bolt pass through the eyes provided in the keys. The bolt 16 is then turned to bring the side walls 12 and 13 into close proximity with the outer faces of the outermost keys. It is not necessary that the walls 12 and 13 be drawn up tightly against the keys but rather that they be drawn only sufficiently close as will permit the keys to be revolved about the bolt 16 without undue friction by pressure from the walls.

To place the free ends of the keys within the holder, the body end 10 is grasped by one hand and the other end over the heads of the bolt 16 is grasped by the other hand and the holder is stretched longitudinally as indicated in Fig. 5 where it has been distorted from the dash line position to some such position as indicated by the solid lines. While in this distorted position, the keys may be rocked down from the solid line position to the dash line position so as to have the free ends directed toward the interior of the body 10 so that when the body 10 is released, these free ends will be covered over by the pocket 11 and entered therein so that as long as the holder is in its normal undistorted condition, the keys are effectively retained between the side walls and within the pocket 11 and cannot be used until the holder is again distorted to permit clearance of the ends of the keys so that the keys may be revolved about the bolt 16 and be extended from the holder.

Thus when one key is outside of the holder and available for use, the other keys are retained within the holder by having their ends retained

within the pocket 11 and the walls of the holder extend from those retained keys in such manner that the retained keys cannot strike against the walls or plates about the key hole into which the 5 available key is inserted. It is to be seen that there is a great advantage in the use of a holder as I have described, particularly when it is to be carried in one's pocket since it provides a very compact unit having no snaps or other fasteners 10 to be operated or to protrude and be in the way. It is to be noted that by reason of the frictional engagement of the walls of the holder with the heads of the bolt 16, it is not necessary to abut the two parts of the bolt together to prevent the 15 bolt from loosening or working out so that the same length bolt may be used throughout the range of number of keys which the holder will carry.

While I have herein shown and described my 20 invention in the one best form as now known to me, it is obvious that structural changes may be made without departing from the spirit of the invention and I, therefore, do not desire to be limited to that precise form beyond the limitations as may be imposed by the following claims.

I claim:

1. A key holder comprising a body having a pocket, a wall extending from each of opposite sides of the pocket, and a transversely disposed 30 member carried by the walls adapted to pass through eyes of keys placed between the walls, said member being spaced in relation to said pocket to have the other ends of the keys disposed within the pocket whereby the keys are retained 35 against rocking about the member, and said walls having at least a portion thereof sufficiently elastic to permit elongation thereof so that the keys may be released from said pocket by pulling said member away from said pocket and said pocket 40 being enclosed on all sides requiring end movement of the keys and the transverse member passing through the eyes of the keys for release of the keys from the pocket.

2. A key holder comprising a body having a pocket, a wall extending from each of opposite 45 sides of the pocket, and a transversely disposed member carried by the walls adapted to pass through eyes of keys placed between the walls, said member being spaced in relation to said pocket to have the other ends of the keys disposed 50 within the pocket whereby the keys are retained against rocking about the member, and said walls having at least a portion thereof sufficiently elastic to 55 permit elongation thereof so that the keys may be released from said pocket by pulling said member away from said pocket, said walls being free from one another so as to leave a slot-like opening entering therebetween at least along one set of opposing edges so that keys may be rocked about said member through that opening when released from the pocket and said pocket being 60 enclosed on all sides requiring end movement of the keys and the transverse member passing through the eyes of the keys for release of the 65 keys from the pocket.

3. A holder for keys comprising a body having a pocket formed therein to receive ends of keys, an 70 elastic rubber wall extending from each of a pair of opposing sides of the pocket, one wall being carried by the pocket independently of the other wall, and a bolt carried by and extending transversely across between the walls spaced from the pocket to have keys threaded on the bolt to ex-

tend into the pocket and said pocket being enclosed on all sides requiring end movement of the keys and the transverse member passing through the eyes of the keys for release of the keys from the pocket.

4. A holder for keys comprising a body having a pocket enclosed on all sides formed therein to receive ends of keys, an elastic rubber wall extending from each of a pair of opposing sides of the pocket, one wall being carried by the pocket independently of the other wall, and a bolt carried by and extending transversely across between the walls spaced from the pocket to have keys threaded on the bolt to extend into the pocket and released from the pocket by increasing the 10 distance between the pocket and bolt to stretch the walls, said bolt being in two parts, and each of said parts being frictionally engaged by said walls.

5. A holder for keys comprising a body having a pocket enclosed on all sides formed therein to receive ends of keys, an elastic rubber wall extending from each of a pair of opposing sides of the pocket, one wall being carried by the pocket independently of the other wall, and a bolt carried by and extending transversely across between the walls spaced from the pocket to have keys threaded on the bolt to extend into the pocket and released from the pocket by increasing the 15 distance between the pocket and bolt to stretch the walls, said bolt being in two parts, and annular rubber rings on the walls peripherally and elastically engaging the respective bolt parts.

6. A key holder comprising a body having a pocket, a wall extending from each of opposite 35 sides of the pocket, said pocket being enclosed on all sides except in the direction of the wall extensions, and a transversely disposed member carried by the walls adapted to pass through 40 eyes of keys placed between the walls, said member being spaced in relation to said pocket to have the other ends of the keys disposed within the pocket whereby the keys are retained against 45 rocking about the member, and said walls having at least a portion thereof sufficiently elastic to permit elongation thereof so that the keys may be released from said pocket by pulling said member away from said pocket, said walls being free 50 from one another so as to leave a slot-like opening entering therebetween at least along one set of opposing edges so that keys may be rocked about said member through that opening when released from the pocket, and a boss on one side of said body providing a key locating and finger 55 gripping member.

7. A holder for keys comprising an elastic rubber body having a pocket therein opening from one end only and enclosed in all other directions, an elastic rubber wall extending from the body 60 from each of two opposing edges of said opening and each wall having a hole therethrough near its outer end and a rib around the edges of each wall, and a key carrying bolt through said holes.

8. A holder for keys comprising an elastic rubber body having a pocket therein opening from one end only and enclosed in all other directions, an elastic rubber wall extending from the body 65 from each of two opposing edges of said opening and each wall having a hole therethrough near its outer end, and a key carrying bolt through said holes, annular bosses on said walls about said holes, and said bosses elastically gripping said bolt.
